UNITED STATES PATENT OFFICE.

CHARLES E. ALDRED, OF CAIRO, ILLINOIS.

WEATHER-STRIP.

1,035,070.

Specification of Letters Patent.

Patented Aug. 6, 1912.

Application filed May 3, 1910. Serial No. 559,051.

To all whom it may concern:

Be it known that I, CHARLES E. ALDRED, a citizen of the United States, residing at Cairo, in the county of Alexander and State 5 of Illinois, have invented new and useful Improvements in Weather-Strips, of which the following is a specification.

This invention relates to weather strips and particularly to that type which are 10 adaptable for outside doors or French windows.

The object of the invention is the provision of means for automatically projecting a strip into engagement with the frame of 15 the door or window or into engagement with its sill when such door or window is closed and to automatically retract said strip when the door is opened.

Further objects of the invention will appear as the specific description which follows is read in connection with the accompanying drawings which form a part of 20 this application, and in which:—

Figure 1 is a broken elevation of the device attached to the door. Fig. 2 is an inside elevation of the device removed from the door. Fig. 3 is a transverse section taken on the line 3—3 of Fig. 2.

Referring more especially to the drawing, 30 1 represents the door or window to which the device is attached, and 2 represents the frame of said door or window. Secured to the bottom edge of the door or window is a guard strip 3 which is preferably constructed of sheet metal of suitable gage. 35 This guard strip extends from either side of the door across the bottom and engages the door or window at its top.

Rigidly secured to the inner side of the 40 guard strip adjacent each end thereof are suitable guiding ribs 4 which have T-heads 5 and are apertured as at 6 to receive the operating rod 7 which is slidably mounted therein. This operating rod projects beyond the end of the strip and has secured 45 thereupon an elongated nut 8 which may be adjusted to secure a proper contact with the door frame and to cause the operating rod 7 to travel a proper distance to engage 50 the sill or frame. A spiral spring surrounds the rod between an adjustable collar

9 and one of the guiding strips 10 so as to normally retract the rod and keep it in position whereby the nut will engage the frame.

Pivotedly mounted on the guard strip intermediate the guiding ribs are a pair of bell crank levers 11 having their longer arms pivotally connected with the operating rod 7. Their short arms are beveled off as at 12 to present a cam face which 55 rides upon the inside edge of the reciprocating strip 13. This strip is slotted so as to receive the guiding ribs and be guided thereby in its movement and on its outer edge is provided with a sill engaging felt or 60 rubber strip 14. When the rod is moved by its engagement with the frame, the bell crank levers engage the inner end of the strip 13, and force it downwardly so as to bring the strip 14 into engagement with 65 the sill or frame.

In order to retract the strip automatically with the opening of the door or window, I secure to the inner edge of the strip screw eyes 15 and from each screw eye there 70 is led a flexible connecting device such as a cord or chain 16 to connection with the rod 7. These connecting devices travel over suitable pulleys 17 which are revolvably mounted upon stub shafts 18 projecting 75 from the inner face of the guard strip. From the above, it will be seen, that when the rod 7 is moved to normal position by the spring, the flexible connectors will cause the strip 13 to travel with the movement of 80 the short legs of the bell crank levers 11 85 and be in continuous engagement therewith.

Having thus described the invention, what is claimed is:—

In a device of the class described, the 90 combination with a door, of a guard strip mounted thereon, guiding members secured to the inner side of said strip, a weather strip slidably mounted between the door and the guard strip and having slots to receive said guiding members, means carried by the guiding members to prevent lateral displacement of the weather strip, bell crank levers pivoted to the guard strip and having cam ends 95 12 100 freely engaging said weather strip, and an operating rod slidably mounted in the

guiding members and pivotally connected to the bell crank levers for operating the same, an adjustable collar on the rod, a spring surrounding the operating rod between the 5 collar and one of the guiding members for normally retracting the rod, pulleys on the guard strip, flexible members connecting the weather strip and rod, and passing over

said pulleys, substantially as and for the purpose described.

In testimony whereof I affix my signature in presence of two witnesses.

CHARLES E. ALDRED.
